UNITED STATES PATENT OFFICE.

SAMUEL CHITTENDEN, OF WILLIMANTIC, CONNECTICUT.

SPRING FOR VEHICLES.

SPECIFICATION forming part of Letters Patent No. 248,023, dated October 11, 1881.

Application filed July 20, 1881. (No model.)

To all whom it may concern:

Be it known that I, SAMUEL CHITTENDEN, a citizen of the United States, residing at Willimantic, in the county of Windham, and 5 State of Connecticut, have invented certain new and useful Improvements in Springs for Vehicles; and I do hereby declare the following to be a full, clear, and exact description of the invention, such as will enable others skilled 10 in the art to which it appertains to make and use the same, reference being had to the accompanying drawing, and to letters or figures of reference marked thereon, which form a part of this specification.

15 This invention relates to certain improvements in the combined elliptic and tortuous vehicle-spring described in a former application.

In the drawing, A represents the outer elliptic, and B represents the inner tortuous, spring, which are of substantially the same construction in themselves as those described in my before-mentioned allowed application.

It has been found in practice that the downward pressure of the body of the vehicle causes the inner ends or curves, *a b*, of the tortuous spring B to bend down, and thereby lose their elasticity and also incur the danger of being broken. This is especially the case when the 20 vehicle is heavily loaded and the weight on one end of the spring is in excess of the weight on the other end. It is also found that when the vehicle is heavily loaded and subjected to a sudden jostling the curvatures *a b* will turn 25 downward and the greatest strain will be exerted thereon, rendering them very liable to fracture. To obviate these difficulties and prevent the downturning of the curved ends *a b*, I secure said ends together by means of a link, 30 C, which, as shown in the drawing, is passed around the ends and across the space intervening between them, so as to hold them together

without affecting their individual yielding movement, excepting that by this arrangement the ends are prevented from turning downward and the weight is more evenly distributed over both portions of the spring than is the case where the ends *a b* are not connected together.

D represents one of the hanging bars. In 50 the underface of said bar D is a deep concavity, into which the entire top portion of the outer or elliptic spring, A, fits, and I extend the ends of said bar beyond the outer ends of the elliptic spring and bolt or otherwise secure the 55 springs and hanging bar and axle together, as shown at *c c*.

By constructing the bar D to receive the top portion of the spring A and similarly curving the upper face of the axle E, I secure improved bearing-surfaces for the spring, and am also enabled to dispense with the leaf or additional reinforcement of metal usually employed in conjunction with elliptic springs.

Having thus described my invention, what 65 I claim as new therein is—

1. The combination of the hanging bar D, recessed on its under face, the axle E, recessed on its upper face, the outer elliptic spring, A, the inner tortuous spring, B, link C, and fastenings *c c* for securing said bar, axle, and springs together, substantially as and for the purpose set forth.

2. The combination of the outer elliptic spring, A, the inner tortuous spring, B, and 75 the link C, substantially as and for the purpose set forth.

In testimony whereof I affix my signature in presence of two witnesses.

SAMUEL CHITTENDEN.
